Primary Examiner — Janice Patyk(74) *Attorney, Agent, or Firm* — KPPB LLP(57) **CLAIM**

The ornamental design for a media playback device, as shown and described.

DESCRIPTION

FIG. 1 is a front elevation view of a media playback device of the present invention.

FIG. 2 is rear elevation view thereof.

FIG. 3 is a first side view thereof.

FIG. 4 is a second side view thereof.

FIG. 5 is a top plan view thereof.

FIG. 6 is a bottom plan view thereof; and,

FIG. 7 is a perspective view thereof.

The broken lines illustrate portions of the media playback device that form no part of the claimed design.
